ELECTRONIC CYCLE COUNTING CIRCUIT

Joseph C. Tellier, Penn Wynne, Pa., assignor to
Philco Corporation, Philadelphia, Pa., a corpora-
tion of Pennsylvania

Application June 12, 1947, Serial No. 754,196

3 Claims. (Cl. 250—27)

1

This invention relates to circuits for counting the cycles of a periodic voltage, and has for its principal object the provision of a novel circuit for the stated purpose. The present application is a continuation-in-part of application Serial No. 566,739, filed December 5, 1944 now abandoned.

Prior circuits designed and adapted to accomplish the general purpose above-stated are commonly characterized in that they count the cycles of a periodic voltage by adding voltages produced in response to the successive cycles of the applied voltage, and by triggering an indicating circuit when the resultant or summation voltage reaches a certain magnitude or value. Such devices have been subject to error due to variations or changes in the circuit components, such as resistors, which are employed, and due also to variation of the signal or voltage under observation. Thus variations or changes in bias, triggering level, signal voltage, etc. may produce a false count of the cycles and thus give rise to error.

One object of the present invention is to provide a cycle counting circuit which is free of such objections of prior devices of this general class.

Another object of the invention is to provide a novel cycle counting circuit which counts the cycles of a periodic voltage directly rather than by summing voltage produced in response to successive cycles.

A further object of the invention is to provide a cycle counting circuit which effectively counts the number of times a periodic voltage reaches its maximum value and thus accurately counts the cycles thereof.

The invention may be clearly understood by reference to the accompanying drawing, in which:

Fig. 1 is a diagrammatic illustration of a preferred form of the invention; and

Fig. 2 illustrates one form of periodic wave for purposes of explanation.

Referring to Fig. 1 of the drawing, there is represented at E a source of a periodic voltage whose cycles are to be counted. Connected to the source E is the novel circuit of the present invention, which comprises a plurality of series-connected energy-storing devices which preferably take the form of capacitors designated C₁, C₂, C₃ and C₄ respectively. While four capacitors are shown in the specific illustration, the number may be varied, as will be apparent later. The circuit further comprises a corresponding plu-

rality of shunt-connected unilateral conducting devices which preferably take the form of diodes designated D₁, D₂, D₃, and D₄ respectively. These unilateral conducting devices are connected respectively to the output sides of the energy-storing devices or capacitors. Moreover, consecutive ones of the unilateral conducting devices, or diodes, are connected in reverse conducting relation to their associated or corresponding energy-storing devices. Thus the first diode D₁ has its anode connected to the output side of the first capacitor C₁, the second diode D₂ has its cathode connected to the output side of the second capacitor C₂, and so on. The reason for this reverse connection of the consecutive diodes will be apparent presently. Preferably the source E and the diodes are connected to ground as illustrated, so that one side of the source and one of the electrodes of each diode are maintained at a fixed (ground) potential.

In operation, the circuit effectively counts the number of times the voltage of source E reaches its maximum value. This counting function is accomplished through a mode of operation in which the series of capacitors, C₁, C₂, C₃, and C₄, are successively charged, each succeeding capacitor receiving its charge from a preceding capacitor each time the applied voltage alternates from one maximum value to the other. For simplicity, it may be assumed that the voltage of source E is a simple sine wave W, as shown in Fig. 2, which varies from 0 to 20 volts. Assume further that all of the capacitors or condensers are initially discharged when the periodic voltage of source E is applied to the input of the circuit, and that the capacity values of the capacitors are such that, in operation, each succeeding capacitor is charged to approximately the full input voltage without substantially reducing the charge on the preceding capacitor. This may be accomplished by making the capacity of each succeeding capacitor substantially smaller than the capacity of the immediately preceding capacitor. Under these conditions the operation of the system is as follows:

As the input voltage increases from 0 to +20 volts during time t₁, the condenser C₁ is charged to approximately the full 20 volts through its associated diode D₁. Since the voltage at point 1 cannot go positive, no further operation occurs during the increase of the applied voltage.

As the applied voltage decreases from its maximum positive value to its maximum negative value during time t₂, the voltage at point 1 decreases to -40 because of the voltage across con-

denser C_1 , and at the same time, the condenser C_2 is charged through its associated diode D_2 and the condenser C_1 . At this time the diode D_1 is non-conductive. Since point 2 cannot go negative, no further operation occurs during the decrease of the applied voltage.

As the applied voltage again increases to +20 volts during time t_3 , the voltage at point 1 increases to 0, and the voltage at point 2 is increased to +40 volts due to the voltage drop across condenser C_2 . During this portion of the cycle, the diode D_1 is blocked by the back voltage across condenser C_1 , and of course the diode D_2 is non-conductive. The diode D_3 , however, is conductive, and condenser C_3 is charged through this diode. Since point 3 cannot go positive, no further operation occurs during this portion of the wave cycle.

When the applied voltage again decreases from its maximum positive value to its maximum negative value during time t_4 , the voltage at point 1 decreases to -40 volts, the voltage at point 2 decreases to 0, and the voltage at point 3 is decreased to -40 volts by the voltage drop across condenser C_3 . At the same time the condenser C_4 is charged through its associated diode D_4 , the other diodes being non-conductive. As the applied voltage again increases during t_5 , an output voltage appears at point 4, which indicates that two cycles of the applied voltage wave have elapsed. The output voltage may be applied to any specific use. While the present invention is not concerned with the particular use to which the circuit may be applied, it may be noted that the circuit may be used as a timer, or as a frequency divider. For example, it may be used to cause operation of another circuit after a certain number of cycles of the applied voltage have elapsed.

It will be noted that the operation of the circuit involves successive charging of the condensers or capacitors in response to successive portions of the applied voltage until an output voltage appears after a certain number of cycles have elapsed, depending upon the number of capacitors and associated diodes. It will also be noted that each succeeding pair of capacitors and their associated diodes constitute a stage which responds to one cycle of the applied voltage. Thus the circuit comprises a plurality of cascaded stages, which respond in succession to successive cycles of the applied voltage. Within practical limits the number of such stages may be varied at will so as to vary the number of cycles which are counted during a complete operation of a circuit.

While the circuit of Fig. 1 has been described with reference to the sine wave of Fig. 2, it is capable of counting the cycles of any periodic voltage, such as a pulse signal, a square wave, a saw-tooth wave, etc. In any case, the circuit operates in the manner above described, the condensers being successively charged in response to periodic increase and decrease of the applied voltage.

When circuits constructed in accordance with the principles of the present invention comprise a large number of cascaded stages, it may be

impractical to make the capacity of each succeeding capacitor substantially smaller than that of the preceding one, due to the great range of capacitance values which would then result.

5 Under these circumstances the capacitance values of the condensers are preferably equal. A typical capacitance value under these conditions is 1,000 micro-microfarads, but the value employed may be selected according to the particular application of the invention in any instance. In any case, the circuit constants should be such that the capacitors are not discharged by leakage during the counting operation sufficiently to interfere with the operation. If desired, suitable resistors may be shunted across the capacitors so as to discharge each capacitor after a desired time.

Where the capacitors C_1 , C_2 , etc. are of substantially equal value the operation of the system does not follow precisely the description outlined above.

20 However the circuit has the same cycle counting properties, the chief distinction being that the output voltage is decreased approximately in inverse ratio to the number of condensers in the circuit.

25 Although the invention has been described with reference to the illustrated embodiment, it is not limited thereto but is capable of various modifications within the scope of the appended claims.

I claim:

30 1. A cycle counting circuit comprising, in combination, first and second input terminals, first and second output terminals, the second of said input terminals and the second of said output terminals being connected to a point of fixed potential; a source of periodic voltage whose cycles are to be counted, said source being connected to said input terminals; a plurality of energy storing devices connected in series between the first of said input terminals and the first of said output terminals, there being junctions between said devices; and a corresponding plurality of unilateral conducting devices, one of said unilateral conducting devices being connected between said first and second output terminals, the remaining unilateral conducting devices being connected, respectively, between said junctions and said point of fixed potential, consecutive ones of said unilateral conducting devices being mutually reversed so as to be conductive in opposite directions.

40 2. A cycle counting circuit according to claim 1, wherein said energy storing devices are capacitors.

45 3. A cycle counting circuit according to claim 1, wherein said unilateral conducting devices are space discharge devices, each having an anode and a cathode.
